UNITED STATES PATENT OFFICE.

JOHN J. MEDVEC, OF MINNEAPOLIS, MINNESOTA.

CUSHION-STRIP FOR BILLIARD AND POOL TABLES.

1,074,279.

Specification of Letters Patent. Patented Sept. 30, 1913.

Application filed October 25, 1912. Serial No. 727,739.

To all whom it may concern:

Be it known that I, JOHN J. MEDVEC, a citizen of the United States, residing at Minneapolis, in the county of Hennepin 5 and State of Minnesota, have invented certain new and useful Improvements in Cushion-Strips for Billiard and Pool Tables; and I do hereby declare the following to be a full, clear, and exact description of the 10 invention, such as will enable others skilled in the art to which it appertains to make and use the same.

My invention relates to billiard and pool tables, and has for its object to provide for 15 use in connection therewith, inset strips adapted to be applied under the cushions of the rails in such manner as not to interfere with the normal cushioning actions of the cushions on the balls. These strips are 20 adapted to be marked with various words or characters serving either as advertisements or to state certain rules or facts connected with the games played on the tables.

In the accompanying drawings which 25 illustrate the invention, like characters indicate like parts throughout the several views.

Referring to the drawings, Figure 1 is a perspective view showing a billiard table having the improved strips applied under 30 the cushions thereof; Fig. 2 is a detail in section taken approximately on the line $x^2 x^2$ on Fig. 1; and Fig. 3 is a fragmentary sectional view in perspective, showing the same parts that are shown in Fig. 2.

Of the parts of the table, all of which are 35 of standard well known construction, it is only desirable to note the framework 1, the table slab 2, the rails 3, and the rail cushioning strips 4. The numeral 5 indicates balls, 40 and the numeral 6 a cue.

The strips that are to be inserted under the cushions may be constructed of different materials, but should be approximately triangular in cross section with the exposed 45 face of the triangle made concave. Preferably, these strips are made from two sheets or strips of thin metal, one of which, to-wit, the member 7, being bent concavo-convex or channel-shaped in cross section,

and the other member 7^a being made V- 50 shaped in cross section. These two strips are connected at their edges by solder, or otherwise, so that they make up a hollow bar. The V-shaped section 7^a has the proper angle to closely fit the angle between the 55 table slab and the under face of the cushion 4 and lower portion of the rail 3. These strips are adapted to be secured in working position by small screws 8, preferably applied as shown in Fig. 2. The strips must 60 be of such cross section that very considerable portions of the angular inner edges of the cushions 4 will be exposed for proper cushioning actions on the balls.

The exposed faces of the concave portions 65 7 may be marked with advertising matter, with notices or rules relating to the game, or with any other useful matter or information.

The improved strips are, of course, 70 adapted for application to pool tables as well as billiard tables.

What I claim is:

1. The combination with a billiard or 75 pool table having rails with angular cushioning strips applied thereto, of angular strips closely fitting the angle between the table and the cushioning strips and securely held in working position with the angular inner edges of the cushioning strips exposed 80 for action on the balls, substantially as described.

2. The combination with a billiard or 85 pool table having rails with angular cushioning strips applied thereto, of angular strips having concave inner faces, the angular portions of said inverted strips closely fitting the angle between the table and the cushioning strips and securely held in working position with the angular inner edges 90 of the cushioning strips exposed for action on the balls, substantially as described.

3. The combination with a billiard or 95 pool table having rails with angular cushion strips applied thereto, of angular strips having concave inner faces, the angular portions of said inverted strips closely fitting the angle between the table and the cushion

strips and securely held in working position with the angular inner edges of the cushion strips exposed for action on the balls, the inner faces of the said inverted strips being marked with words or characters exposed to the view of the players.

In testimony whereof I affix my signature in presence of two witnesses.

JOHN J. MEDVEC.
